UNITED STATES PATENT OFFICE.

OTTO VOGEL, OF DUSSELDORF-OBERKASSEL, GERMANY.

P.D.

PICKLING BATH AND PROCESS FOR PICKLING IRON AND STEEL.

No Drawing.

Application filed August 27, 1921. Serial No. 495,954.

To all whom it may concern:

Be it known that I, OTTO VOGEL, chemist, a citizen of Germany, residing at Wil-
denbruchstreet 52, Dusseldorf-Oberkassel,
5 Germany, have invented certain new and
useful Improvements in Pickling Baths and
Processes for Pickling Iron and Steel, of
which the following is a specification.

The present invention refers to a pickling
10 bath and a process for pickling iron and
steel, malleable iron, wrought iron, iron
alloys as nickel-, chromium-, tungsten-, etc.
steel.

In pickling such iron and iron articles
15 by means of acids and acid substances dis-
solving iron oxides in order to give the iron
a clean or smooth surface the iron and arti-
cles from it becomes brittle. In order to
20 prevent this disadvantage the new pickling
bath contains besides the acids or acid sub-
stances aromatic compounds having a ring
nucleus in which several carbon atoms are
25 united with a nitrogen atom. Suitable com-
pounds are chinoline derivatives, as coal tar
chinoline, synthetical chinoline, isochino-
line, substituted chinoline compounds as
30 acridine, alphanaphthochinoline, betanaph-
thochinoline, chinoline yellow, soluble in
alcohol or water. Also extracts by means
35 of acids from the fractions containing such
bases, obtained in the distillation of coal
tar are suitable. One may also use such
fractions from the distillation of coal tar
containing such bases. Also the syntheti-
40 cally made products may be added to the
pickling bath. For instance the raw prod-
uct from the synthetical production of
chinoline or naphthochinoline or the molten
mass from the production of chinoline yel-
low may be immediately used without puri-
fication. The amounts of the said additions

may be varied. A favourable action may be
obtained even by small additions or solu-
tions of low percentage. A suitable pick-
ling bath consists of mineral acids, as sul-
phuric or hydrochloric acid, or organic
45 acids, as acetic acid, or mixtures of mineral
and organic acids, or solutions of sodium
bisulphate, or mixtures of sodium bisulphate
with acids and 1% of chinoline compounds.
50

The process for pickling consists in that
one adds the chinoline compounds to the
pickling bath before or during the pickling
operation and that one brings the iron or
iron article to be treated in this bath until
55 the oxide layer is sufficiently removed. Then
one takes the iron from the bath, washes it
with water or bases, as lime hydrate, soda
lye or such like and water and dries the
iron.

I claim:—

1. Pickling bath for iron consisting in
acid substances dissolving iron oxides and
aromatic compounds having a nucleus in
which several carbon atoms are united with
65 a nitrogen atom.

2. Pickling bath for iron consisting in
acid substances dissolving iron oxides and
chinoline compounds.

3. The process for pickling iron which
70 consists in bringing iron into a bath con-
taining acid substances dissolving iron ox-
ides and aromatic compounds having a nu-
cleus in which several carbon atoms are
united with a nitrogen atom.

4. The process for pickling iron which
75 consists in bringing iron into a bath contain-
ing acid substances dissolving iron oxides
and chinoline compounds.

In testimony whereof I hereunto affix my
80 signature.

OTTO VOGEL.

Benzyl acridine
